CLAIM

The ornamental design for an ink tank for printing machine, as shown and described.

DESCRIPTION

FIG. 1 is a front, right perspective view of the ink tank for printing machine;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear, left perspective view thereof.

The evenly spaced broken lines depict parts of the ink tank for printing machine that form no part of the claimed design. The dot-dash chain lines depict a boundary of the claimed subject matter and form no part of the claimed design.
